(57) **CLAIM**

The ornamental design for a pelvic floor muscle therapy device, as shown and described.

DESCRIPTION

FIG. 1 is a top, front, right side perspective view of a pelvic floor muscle therapy device, showing my new design; FIG. 2 is a bottom, rear, right side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof. The evenly dashed broken lines illustrate portions of the pelvic floor muscle therapy device and form no part of the claimed design.
